CHIMNEY PIT DOOR

Albert P. Robinson, Seattle, Wash.

Application November 18, 1946, Serial No. 710,585

2 Claims. (Cl. 189—46)

1

This invention relates to improvements in articles of that kind which are known in the home building industry as "chimney pit doors"; such doors being applied to the openings provided at the lower end of the chimney of a furnace or fireplace for the removal of ashes and in many cases are located at the outside of the building.

It is the principal object of this invention to provide a chimney pit door and frame therefore that may be set within the chimney wall and, by reason of its novel details of construction, will overcome the undesirable features and disadvantages of present day doors for the same purposes that project from the wall. Furthermore, to provide a door frame structure that will serve to support the brick work above the opening.

It is also one of the principal objects of this invention to provide a frame and door combination including novel features for holding the door securely in its closed position without the use of hinges or pin connections, and which permits ease and ready removal of the door for clean out purposes.

Still another object of the invention is to provide a combination of door and frame that prevents water draining therethrough into the chimney pit and overcomes the detrimental effects of such draining.

Yet another object of the invention is to provide a frame and door structure that can be manufactured at a lesser cost than that of the usual types, by reason of the elimination of difficult casting problems.

Still other objects of the invention are to be found in the details of construction and combination of parts embodied in the structure, and in the mode of use of the device, as will hereinafter be fully described.

In accomplishing these and other objects of the invention, I have provided the improved details of construction, the preferred forms of which are illustrated in the accompanying drawings wherein:

Fig. 1 is a perspective view of a chimney pit door structure embodied by the present invention.

Fig. 2 is a front view of the same with parts thereof broken away to reduce the size of the view and for better illustration of important details of construction.

Fig. 3 is a vertical section, taken on the line 3—3 in Fig. 2.

Fig. 4 is a similar sectional view illustrating the manner of shifting the door upwardly to release it for removal from its frame.

Fig. 5 is a horizontal section taken substantially on the line 5—5 in Fig. 3.

Referring more in details to the drawings:

The present structure comprises a frame portion and an independent door portion. The frame portion is of rectangular form and it comprises

the top and bottom rails, 1 and 2, and opposite end rails 3 and 4; all rails being integrally cast of steel, or other suitable metal or material.

As shown best in the cross sectional views of Figs. 3 and 4, the top rail comprises a flat, horizontally extending portion upon which the brick work that is directly above the opening may be supported. Along its forward edge and flush therewith, this rail has a depending flange 1x. The bottom rail 2, likewise, comprises a flat horizontally extending portion that rests flatly upon the brick work at the bottom of the opening and this has an upwardly directed flange 2x along its forward edge. The opposite end rails, 3 and 4, of the frame structure are set flush with the ends of the top and bottom rails and as shown in Fig. 5, are provided with integrally formed inwardly directed flanges 3x and 4x along their inner edges that are flush with the flange 2x but are inset from the plane of the flange 1x to a slight extent as has been shown in Figs. 3 and 4. Also, the flanges 3x and 4x are formed along their inner longitudinal edges, at the front side, with longitudinal beads designated at 6, which terminate at their upper and lower ends short of the rails 1 and 2, as will be understood by reference to the showing of the beads in Fig. 3.

The door 10 comprises a single piece, integrally cast member of rectangular form and equipped along its top edge with an inwardly offset and vertically directed flange 11 adapted to be received back of the outside flange 1x that depends from the forward edge of the top rail 1. Along its opposite sides, the door 10 has inwardly formed edge portions or flanges 12 that are designed to engage flatly against the outside surfaces of the flanges 3x and 4x of the end rails 3 and 4 outside of the beads 6, as shown best in Fig. 5. Across the bottom of the door, there is a flat, vertically depending flange 13 that is designed to fit closely against the front face of the flange 2x of the bottom rail 2 when the door is in its closed position, and formed on the door, at the inside thereof, near its lower edge and centrally between its ends, is an inwardly and downwardly directed tongue 15, adapted to extend over and to the inside of the flange 2x, to rest thereagainst as a means of retaining the door in a closed position; this being the position in which the door is shown in Fig. 3.

To facilitate the opening or removal of the door, it is formed centrally at its lower edge, and at the outside, with a handle lip 18.

It is shown in Figs. 3 and 4 that the main body portion of the door casting is outwardly formed. The boundaries of this outwardly formed portion are inclined inwardly to various edge flanges. Thus there are no abrupt bends, or shoulders of a character that will catch dust and dirt, or retain water thereon. Water that

drains from the brick work on to the door from above will be directed to the outside of the frame structure and not to the inside, thus overcoming the undesirable and detrimental effects of water leakage into the ash pit.

When the door is in its closed position, as in Fig. 3, there is sufficient clearance between the top edge of the top marginal flange 11 of the door and the flat portion of top rail 1 to permit the door to be lifted upwardly and the tongue 15 to be disengaged from the lower flange 2x of the bottom rail 2. With the door so lifted, it may then be pulled outwardly at its lower edge and freed from the rail 2. Then the door may be slipped bodily downward to disengage the top marginal flange 11 from the top rail flange 1x so that the door may be removed entirely from the frame structure. To replace the door, its top edge flange 11 is first disposed back of the depending flange 1x of the bottom rail 2, then is lifted upwardly so that the tongue 15 may be passed over and engaged with the flange 2x of the cross bar 2. The door then is lowered slightly and all parts are thereby brought tightly to closed position by the action of the tongue as engaged with the cross flange of the bottom rail 2. When closed, the door assumes the position shown in Fig. 3. It will be understood, that when the door is in this closed position, the depending flange 1x substantially overlaps the top edge of the door. Also, that the vertical, side edge portions of the door engage tightly with the outside surfaces of the end rails 3 and 4 at the outside of the beads 6 thereon, and the lower edge flange of the door overlies the outside of the bottom rail 2. Thus, all joints are tightly closed and no leakage possible under ordinary conditions.

Structures of this character are desirable and advantageous for various reasons:

First, the entire structure may be set within the opening of the brickwork so that the door lies within the front plane of the wall, thus to eliminate as much as possible the catching of dirt on the door.

Second, there are no projecting hinge parts or catches that are not only expensive to cast, but are dust catchers and not desirable.

Having thus described my invention, what I claim as new therein, and desire to secure by Letters Patent is:

1. An ash pit door structure comprising in combination: a rectangular frame adapted for disposition and securing within a wall opening

and comprising top and bottom rails and opposite end rails; said top rail having a depending flange at the front edge thereof, and said bottom rail having an upstanding flange at its front edge and a door removably applied to said frame having an inwardly and upwardly extending flange across its top edge adapted to be disposed back of the said depending flange and said door being adapted to be closely engaged along its opposite side edges and bottom edge with the front end surfaces of the opposite side and bottom rails of the frame and a tongue projecting inwardly and downwardly from the inside of the door to extend downwardly across and engage with the flange of the bottom rail of the frame for the support and securing of the door in closed position; there being clearance between the top edge of the flange at the top edge of the door and top rail permitting upward shifting of the door when in closed position for the disengaging of the tongue from the flange of the bottom rail.

2. A door as recited in claim 1 wherein the said opposite end rails of the frame have in-turned flanges at their forward edges, in the same plane of the flange of the bottom rail for the flat, engagement of the corresponding edge portions of the door thereagainst, and wherein the said tongue is medially of the side edges and adapted to engage over the said flange of the bottom rail and said flanges of the opposite end rails of the frame having beads formed along their inner edges at the outside, and said door having an outwardly formed body portion and inset edge flanges at opposite side edges to engage the opposite end rails at the outside of said beads.
